UNITED STATES PATENT OFFICE.

CORNELIUS W. VAN RANST, OF DETROIT, MICHIGAN.

VALVE-OPERATING MECHANISM.

Application filed August 7, 1923. Serial No. 656,194.

To all whom it may concern:

Be it known that I, CORNELIUS W. VAN RANST, a citizen of the United States of America, residing at Detroit, in the county 5 of Wayne and State of Michigan, have invented certain new and useful Improvements in Valve-Operating Mechanism, of which the following is a specification, reference being had therein to the accompanying 10 drawings.

The invention relates to a valve operating mechanism of a construction particularly adapted for use with internal combustion engines of the V-type having a small included 15 angle between the opposite banks of cylinders.

In my construction, I employ a single cam shaft for actuating the inlet and exhaust valves for all of the cylinders, using rocker 20 arms for transmitting the movement from the cams to the valves.

The primary object of my invention is to obtain a construction in which the inlet valves in opposite banks of cylinders are 25 held open for the same periods of time in their respective cycles and are accelerated and de-accelerated at the same rates. To obtain these results, I have employed the novel features of construction which are, 30 hereinafter fully described.

In the drawings:—

Figure 1 is a transverse section through an internal combustion engine;

Figure 2 is a diagram illustrating the 35 movements of the rocker arm rollers;

Figure 3 represents the acceleration curves of the valves;

Figure 4 shows two superposed cams for actuating the inlet valves on opposite sides 40 of the cam shaft illustrating the difference in their profiles.

A represents a cylinder block having the opposite sets of cylinder bores B and B' arranged at a slight inclination to the vertical. 45 C is a cylinder head suitably secured to the cylinder block and provided with guides D for the inlet valves E and E' which are symmetrically arranged on opposite sides of the median line of the engine to communicate 50 respectively with the cylinders B and B'. F is a cam shaft journaled in the cylinder head and arranged longitudinally therewithin. G and G' are rockers coaxially mounted upon a common shaft H arranged above the 55 cam shaft F. One end of each rocker arm engages the stem of the valves E and E'

while the opposite end of the rocker arm is arranged at an angle thereto and provided with a roller I for engaging the cam shaft F. J and J' are cams longitudinally spaced 60 upon the cam shaft F to engage the rollers of the respective rockers G and G'.

With a construction as described, the rotation of the cam shaft F causes the opening and closing of the inlet valves E and E' 65 by the riding of the rollers I upon the respective cams J and J'. In the usual type of cam shaft all of the inlet cams are of exactly the same contour in order that the inlet valves will be opened for the same 70 periods of time in the respective cylinders. I have discovered, however, that if the inlet cams J and J' are made of the identical contour, the valves E and E' are not opened uniformly but that there is considerable 75 variation in their acceleration. This is due to the angularity of the rocker arms since they are disposed upon opposite sides of the rotating cam shaft F. Referring now to Figure 2, if the cams J² and J³ are of the 80 same contour, the rollers I and I' will be actuated from the positions K and K' to L and L' respectively. This results in an angular movement of the roller I in a clockwise direction through the angle M and a corresponding counter-clockwise rotation of the roller I' through the angle M'. The cam shaft F, however, always rotates in one direction, for instance, counter-clockwise. Therefore, the engagement of the cam J² 85 and roller I causes the acceleration of the roller at a different rate from the roller I'. Figure 3 illustrates the acceleration curves of the opposite inlet valves when cams of identical contour are employed, the line N 90 representing the curve of the roller I and the curve N' representing the roller I'.

In order to overcome the difficulty above mentioned I have provided cams of different contour for actuating the inlet valves on opposite sides of the cam shaft and these cams are so proportioned that identical acceleration curves are obtained, thereby insuring uniformity in performance of the different cylinders of the engine. As shown in Figure 4, the cams J and J' are considerably 100 different in their profile but when arranged on the cam shaft to cooperate with the oppositely arranged rocker arms G and G' the inlet valves E and E' are opened exactly 105 the same amount and at the same rate of acceleration.

What I claim as my invention is:—

1. In an internal combustion engine, the combination with a cam shaft and an inlet valve on each side thereof, of a pair of co-axially mounted rockers engaging the respective valves, and separate cams on said cam shaft engaging the respective rockers, said cams having different contours such as to impart the same opening and closing movement 10 to the opposite valves.

2. In an internal combustion engine, the combination with a pair of cylinders upon opposite sides of the median line of the engine, a longitudinally extending cam shaft, 15 inlet valves in said cylinders, a pair of rockers engaging the respective valves and symmetrically arranged with respect to said cam shaft, and separate cams on said cam shaft

engaging the respective rockers, said cams having different contours such as to compensate for the angularity of said rockers and impart identical acceleration to the opposite valves. 20

3. In an internal combustion engine, the combination with a pair of inlet valves, a 25 pair of actuating rockers for said valves, a cam shaft extending transversely to said rockers at equal distances from said valves, rollers mounted upon said rockers, and separate cams upon said cam shaft engaging 30 said rollers, said cams having different contours of such form as to impart the same opening and closing movements to the opposite valves.

In testimony whereof I affix my signature.
CORNELIUS W. VAN RANST.
